UNITED STATES PATENT OFFICE.

JAMES M. McCLELLON, OF EVERETT, MASSACHUSETTS.

FIRE-BOX, &c.

1,111,267.

Specification of Letters Patent. Patented Sept. 22, 1914.

Application filed June 1, 1911. Serial No. 630,553.

To all whom it may concern:

Be it known that I, JAMES M. McCLELLON, a citizen of the United States, and a resident of Everett, in the county of Middlesex and 5 Commonwealth of Massachusetts, have invented an Improvement in Fire-Boxes and other Structures, of which the following description, in connection with the accompanying drawings, is a specification, like characters on the drawings representing like parts.

This invention relates to locomotive fire-boxes, boilers and other structures and more particularly to walls thereof.

15 The character of the invention may be best understood by reference to the following description of illustrative embodiments thereof shown in the accompanying drawings, wherein:

20 Figure 1 is a horizontal section through a wall illustrating an embodiment of the invention; Fig. 2 is a vertical section taken on line 2—2 of Fig. 1; Fig. 3 is a horizontal section of a modification.

25 Referring to the drawings with more particular reference to Figs. 1 and 2, the illustrative embodiment of the wall there shown comprises a plurality of unitary, hollow, upright sections 1 extending side by side transversely to the length of the wall.

30 To provide a wall which will be inextensible and stable as a whole, and at the same time will be of sufficient local or unit flexibility and expansibility to expand and contract in 35 response to variations in temperature without buckling, straining or weakening the wall, each section thereof is made to present a flexible side or portion 3 conveniently curved, bulged or convexed in cross sectional 40 shape at the inner or fire face of the wall.

45 The exterior sides 5 of the sections are not heated and strained to the same extent as the inner sides 3 and therefore do not need to be formed to provide for the same curvature as do the inner sides, although they may be so formed, if desired, or may, and preferably will be formed to present curved sides as shown of less convexity than the opposite or inner sides. The sides of 50 the sections connecting the curved sides 3 and 5, preferably are flattened.

55 In my Patent No. 963,627 dated July 5, 1910, is shown a wall comprising a series of flexion sections having their adjacent walls secured together by rivets distributed at in-

tervals throughout their lengths. While this is a very advantageous construction, yet it is not always easy to have sufficient access to the rivets located midway between the ends of the sections to see that they are 60 properly placed and set.

An important feature of the invention consists in providing each of the flexion sections with inherent or independent stability in order that they may maintain themselves 65 in proper position and relationship and be effective as units of a complete and permanent wall structure without the necessity of the rivets referred to. To this end there may be distributed at intervals throughout 70 the length of each section stay means shown in Figs. 1 and 2 as stay bolts or sleeves 7 contained within and extending transversely across and connecting the flattened sides of a section. These stay sleeves are secured to 75 said sides in such a manner as to prevent movement of said sides in the direction of the length of the series of sections. The ends of the sleeves may be threaded, ex- 80 panded, welded or otherwise secured into apertures in the sides of the sections, the ends of the sleeves herein projecting slightly beyond the exterior faces of said sides where they are headed over or upset as shown at 9. To further secure the sleeves 85 to said sides and prevent any possibility of leakage at their threaded connections to said sides, they may be welded to the latter adjacent their upset ends.

To permit adjoining sections to abut 90 closely against one another, the flattened sides thereof are provided with depressions 10 receiving said upset ends of the stay sleeves and permitting said ends to be flush with the sides of the sections. The stay sleeves, of course, would be applied before the sections are assembled into the wall.

To secure the sections together and permit ready removal of a section for purposes of 100 replacement or repair, there is provided suitable securing means shown in Figs. 1 and 2 as common to said sections, said means herein being in the form of a tie rod 11, of a length sufficient to extend through the registering stay sleeves of the sections and beyond the sides of the end sections of the wall where said tie rod may receive suitable holding nuts or caps 13 threaded thereon. By this construction the rods may be readily inserted and removed and may be held with 110

any desired tightness merely by the adjusting of said nuts. The cap form of nut is desirable since it completely incloses the threaded end of the tie rod and protects the same from rust and presents a pleasing and finished appearance.

Preferably a tie rod will be provided at each stayed interval of a section, but at some intervals the tie rod may be omitted, if desired. The tie rod may also project through plates 15 located at the ends of the fire-box or structure, if desired. When the sections are assembled or connected by a tie rod as described, adjacent ends of the stay sleeves preferably will abut and thereby, in effect, constitute a single stay means extending the length of the wall and will effectually prevent extension of the wall in the direction of its length.

Referring now to Fig. 3 the modification there shown comprises sections 3 similar in contour and general construction to those shown in Figs. 1 and 2, with the exception that instead of stay means comprising sleeves the stay means comprises solid stays or bolts 19 threaded or otherwise secured to sides of the sections and herein having their ends upset to form abutting heads 21 seated in depressions 23 in the flattened sides of the sections and which may be similar to those described in connection with the stay sleeves. As shown herein, the stay bolts are arranged in two vertical rows but one or more rows may be employed as desired. Stay bolts such as described, give the sections sufficient inherent strength to prevent any possibility of displacement of the adjoining sides thereof in the direction of the length of the wall and it is, therefore, unnecessary to provide means for securing the sections together distributed throughout the lengths of the sections, but it is sufficient to secure the upper and lower ends merely of the sections together by rivets or other stable securing means not necessary to show herein.

It is well known that pressure in a container tends to cause the walls thereof to assume a shape of circular cross section. The side of a section facing the interior of the fire box may be convexed or curved to have the shape which the pressure of steam or other fluid in the section would tend to cause said side to assume. As a result this pressure does not tend to distort said side but on the contrary tends to maintain it in its original shape. By similar reasoning, the exterior side of the section tends to maintain its original shape. The opposed curved sides of a section, by their shape, are, therefore, self-sustaining. Where the adjacent sides of the sections are flattened, any pressure tending to curve or distort said sides, is rendered ineffective by the stays or corrugations distributed at intervals substantially throughout their lengths.

It will be understood that the invention is not only applicable to locomotive fire-boxes and boilers but also to other structures.

Having described preferred embodiments of the invention without limiting the same thereto, what I claim as new and desire to secure by Letters Patent, is:

1. A structure of the class described comprising, in combination, a series of upright sections having portions flexible and self-sustaining transversely to the lengths of the sections, and flattened portions, and means inherent to each section for preventing extension of its flattened portions in the direction of the length of the series. 75
2. A structure of the class described comprising, in combination, a series of upright sections having flexible portions, each section having independent means for preventing its extension in the direction of the 80 length of the series.
3. A structure of the class described comprising, in combination, a series of upright unitary sections, each having means connecting opposite portions thereof to localize flexion to other portions. 90
4. A structure of the class described comprising, in combination, a series of upright sections having curved flexible portions and stays connecting other portions thereof and distributed at intervals in the lengths of 95 said sections.
5. A structure of the class described comprising, in combination, a series of upright unitary wall sections having flexible portions and means common to all of said sections for securing them together. 100
6. A structure of the class described comprising, in combination, a series of upright unitary wall sections and means extending through said sections transversely to the lengths thereof for securing them together. 105
7. A structure of the class described comprising, in combination, a series of upright unitary flexion sections and a tie rod common to said sections for securing them together. 110
8. A structure of the class described comprising, in combination, a series of upright unitary sections, a tie rod common to said sections and means co-operating with said tie rod for securing said sections together. 115
9. A structure of the class described comprising, in combination, a series of upright flexion sections and stay sleeves for securing said sections against extension in the direction of the length of the sections. 120
10. A structure of the class described comprising, in combination, a series of upright sections and stay sleeves secured to opposite portions of said sections. 125
11. A structure of the class described comprising, in combination, a series of upright flexion sections, stay sleeves extending transversely of the latter, and a tie rod extend- 130

- ing through said sleeves for securing said sections together.
12. A structure of the class described comprising, in combination, a series of upright flexion sections, stays entered through apertures therein and having heads seated in depressions in said sections. 5
13. A structure of the class described comprising, in combination, a series of upright flexion sections, and stays connecting opposite sides of each section, said stays being arranged in alinement and having abutting ends. 10
14. A structure of the class described comprising, in combination, a series of upright flexion sections, hollow stays connecting opposite sides of each section, said stays being in registration and means extending through said stays for securing said sections together. 15
- 20

15. A structure of the class described comprising, in combination, a series of upright flexion sections arranged side-by-side, and transverse stays in each section connecting and projecting through opposite sides thereof and having enlarged ends seated in opposed depressions in said sections. 25

16. A structure of the class described comprising, in combination, a series of upright flexion sections, transverse stays projecting through sides thereof and having enlarged ends seated in depressions therein to permit close arrangement of said sections. 30

In testimony whereof, I have signed my name to this specification, in the presence of two subscribing witnesses. 35
